H. I. BENEDICT,
LIFTING JACK,
APPLICATION FILED JAN. 5, 1917.

1,234,606.

Patented July 24, 1917.

UNITED STATES PATENT OFFICE.

HENRY I. BENEDICT, OF NEW YORK, N. Y., ASSIGNOR OF ONE-HALF TO ALBERT F. WAGNER, OF NEW YORK, N. Y.

REISSUED

LIFTING-JACK.

1,234,606.

Specification of Letters Patent. Patented July 24, 1917.

Application filed January 5, 1917. Serial No. 140,722.

To all whom it may concern:

Be it known that I, HENRY I. BENEDICT, a citizen of the United States, and a resident of the city of New York, borough of 5 Manhattan, in the county and State of New York, have invented a new and Improved Lifting-Jack, of which the following is a full, clear, and exact description.

This invention relates to lifting jacks of 10 that type in which the movable element embodies a screw which is turned through a crank-operated gearing.

The invention has for its general objects to improve and simplify the construction 15 and operation of devices of this character so as to be reliable and efficient in use, comparatively simple and inexpensive to manufacture, of durable and substantial design, and capable of having a large range of 20 movement, although the jack is of compact construction.

A more specific object of the invention is the provision of a jack in which the elevating element embodies a buttress screw which 25 is engaged by releasable dogs on the vertically movable section of the jack, there being novel means for releasing the dogs so that the jack can be easily and quickly collapsed and at the same time the screw and dogs 30 permit the vertically movable element to be raised or pulled out without operating the gearing, thus enabling the jack to be quickly adjusted to the load or object to be lifted.

With such objects in view, and others 35 which will appear as the description proceeds, the invention comprises various novel features of construction and arrangement of parts which will be set forth with particularity in the following description and 40 claims appended hereto.

In the accompanying drawing, which 45 illustrates one embodiment of the invention and wherein similar characters of reference indicate corresponding parts in all the views,

Figure 1 is a vertical section of the jack with an operating crank applied thereto;

Fig. 2 is a horizontal section on the line 2-2, Fig. 1;

Fig. 3 is a sectional view with portions 50 broken away and showing the dogs released from the buttress screw.

Referring to the drawing, 1 designates the tubular body of the casing which is 55 enlarged at its bottom to accommodate the

gearing, and on the lower end of the casing is removably fastened a bottom plate 2. Extending centrally of the casing is a buttress screw 3 which has fastened to its lower end a gear wheel 4, and between this gear wheel 60 and the bottom plate 2 is a step bearing 5 composed of two balls 6 and 7 resting one on top of the other and confined within a socket 8 on the bottom side of the gearing, the lowermost ball bearing on the bottom 65 plate 2. Meshing with the gear is a pinion 9 fixed on a short shaft 10 journaled in a bearing 11 in the casing, the shaft 10 being inclined at an angle to the axis of the screw and having a squared outer end to receive 70 an operating crank 12.

Slidable in the casing is the vertically movable element 13 in the form of a tube which has on its upper end a load-engaging cap-piece 14. The lower or inner end of 75 the tube 13 is formed with a head 15 recessed at opposite sides to accommodate the dogs 16, which have teeth 17 to engage the threads of the buttress screw. These dogs are carried by springs 18 which yieldingly 80 maintain the dogs engaged with the screw. The teeth of the dogs are so shaped that they will slide upwardly on the threads of the screw, whereas they resist a downward movement on the screw, and it is necessary 85 to release the dogs before the vertically movable section of the jack can be lowered. For this purpose a pushbutton release device is employed, the same consisting of a tube 19 slidable in the outer tube 13, and 90 the lower end engages with the dogs so that by being pressed downwardly the dogs are thrown outwardly from the screw. The upper end of the member 19 has a pushbutton 20 which lies within an opening 21 95 in the cap-piece 14, so that by pressing down on the pushbutton the dogs are released and the jack can be collapsed. The casing is preferably filled with lubricant so that all the moving parts can work with the maximum freedom. A jack of this construction 100 is of neat and attractive appearance, of durable and substantial design, capable of lifting a great load, and can be easily and quickly adjusted by reason of the particular 105 form of dog-releasing means.

From the foregoing description taken in connection with the accompanying drawing, the advantages of the construction and method of operation will be readily under- 110

stood by those skilled in the art to which the invention appertains, and while I have described the principle of operation, together with the device which I now consider to be the best embodiment thereof, I desire to have it understood that the device shown is merely illustrative and that such changes may be made when desired as fall within the scope of the appended claims.

Having thus described my invention, I claim as new and desire to secure by Letters Patent:

1. A jack comprising a body section, a vertically movable section slidable in the body section, a screw in the body section, means for turning the screw, dog on the movable section and normally engaging the screw, and means within the movable section for releasing the dog to permit the movable section to be adjusted independently of the screw.

2. A jack comprising a body section, a vertically movable section, a buttress screw mounted in the body section, dogs on the movable section and normally engaging the screw, a pushbutton device for simultaneously releasing the dogs to permit the movable section to be adjusted independently of the screw.

3. A jack comprising a body section, a tubular movable section, a dog thereon, a screw

extending axially of the said sections and normally engaged by the dog, and a longitudinally movable member surrounding the screw for releasing the dog.

4. A jack comprising a body section, a vertical screw therein, means for turning the screw, a vertically movable section in the body section, dogs on the movable section and having screw-engaging teeth, the threads of the screw and the said teeth being so shaped that the movable section can be pulled outwardly while the screw is stationary, and means within and movable with the movable section for releasing the dogs to permit the movable section to be moved downwardly independently of the screw.

5. A jack comprising a body section, a screw extending vertically therein, a gear on the screw, a step bearing between the bottom of the screw and the bottom of the casing, a pinion meshing with the gear for turning the same, a vertically movable load-carrying element in the casing, dogs thereon for engaging the screw, an inner tubular member within the movable member and normally engaging the dogs, and means at the upper end of the vertically movable member for operating the inner member to release the dogs.

HENRY I. BENEDICT.
